UNITED STATES PATENT OFFICE.

IGNAZ HOFFSÜMMER, OF DÜREN, GERMANY.

PROCESS OF MANUFACTURING PHOTOGRAPHIC PAPERS.

No. 812,204

Specification of Letters Patent.

Patented Feb. 13, 1906.

Application filed September 16, 1905. Serial No. 278,775.

To all whom it may concern:

Be it known that I, IGNAZ HOFFSÜMMER, manufacturer, a subject of the German Emperor, residing at 11 Schenkelstrasse, Düren, 5 Rhine Province, Germany, have invented certain new and useful Improvements in Processes of Manufacturing Photographic Papers, of which the following is a specification.

This invention relates to a process of manufacturing photographic papers, and has for its object to render the process more expeditious and considerably cheaper.

As is well known, papers which are to be employed for photographic purposes may be insulated against the emulsions by applying certain protective layers or by special preparations. Such protective layers and preparations may, according to the respective objects, be formed by means of starch, agar, 15 agar, gelatin, milk, solutions of collodion, wool, and other like preparations. The coating with baryta gelatin customary with many photographic papers is also such a protective layer, although the physical property of the paper is also affected when the last-named preparation is used. The coating with baryta gelatin thus serves less as an actual protective layer than as a means for beautifying it and is intended to smooth and equalize the inequalities of the paper. All the 20 known protective layers and preparations, however, only partially fulfil their object, as it frequently happens that in spite of these protective layers and preparations the emulsions penetrate the paper. Therefore for 25 making such photographic papers only raw paper of very good quality could hitherto be employed, for which reason such photographic papers are comparatively expensive.

Now I have ascertained by experiments 40 that the penetration of the emulsions into the paper may be perfectly prevented by spreading over the raw paper a fibrous protective covering—for instance, of thin paper, fabric, and the like. This fibrous protective covering 45 is laid on the raw paper and combined therewith by means of an adhesive or in other suitable manner. This fibrous layer is then emulsioned, after, if necessary, it has been coated previously with baryta. This 50 improved process for making photographic papers has the advantage of allowing a certain latitude as regards cleanliness and composition in the selection of the raw paper by the application of a fibrous protective layer 55 or covering, as raw paper of lower quality may be employed, whereby the price of the finished papers is considerably reduced.

What I claim as my invention, and desire 60 to secure by Letters Patent, is—

1. A process for making photographic papers, consisting in a fibrous layer being laid over and attached to the raw paper and finally emulsioned said layer, substantially as described.

2. An improved photographic paper consisting of a layer of fibrous material laid over the raw paper and attached thereto by an adhesive substance, substantially as hereinbefore set forth.

In testimony whereof I have signed my name to this specification in the presence of two subscribing witnesses.

IGNAZ HOFFSÜMMER.
